CLAIM

The ornamental design for a photography shooting box, as shown and described.

DESCRIPTION

FIG. 1 is a perspective view of a photography shooting box showing our new design;

FIG. 2 is a front elevational view thereof;

FIG. 3 is a left side view thereof;

FIG. 4 is a right side view thereof;

FIG. 5 is a rear elevational view thereof;

(Continued)

FIG. 6 is a top plan view thereof;
FIG. 7 is a bottom plan view thereof; and,
FIG. 8 is a perspective view of the photography shooting
box when it is folded or collapsed.
The broken lines in the drawings depict portions of the
photography shooting box that form no part of the claimed
design.

1 Claim, 8 Drawing Sheets
